MESNE ASSIGNMENTS, TO KATHERINE L. MAYEHOFF, OF NORWALK, CONNECTICUT

PROCESS OF DYEING TEXTILE MATERIALS

Application filed January 16, 1929. Serial No. 332,963.

My invention relates to processes of dyeing textile materials and more especially silk or wool and has a particular reference to fancy or decorative dyeing whereby certain fancy designs are imprinted on textile materials, such as cloth, etc.

The ordinary method of applying decorative designs in color on finished cloth consists in printing such designs from rolls or plates on which the desired design has been previously engraved or etched. The preparation of such printing rolls or matrices represents an expensive and complicated process, requiring services of skilled artists, engravers, etc. This method, therefore, is practical only in cases when a large amount of cloth must be provided with a uniform design.

In my improved process I provide means for obtaining beautiful and fancy designs by simple methods which do not require any artistic skill. The printing design can be prepared with a single or multiple colors, and the design can be applied to the cloth in several shades or colors with a single impression.

For this purpose I provide a printing body with a thin gelatinous layer on which drops of solutions of aniline dyes are placed. The dye spreads out in a very thin layer of practically 80 molecular dimensions. Its particles are subjected to molecular bombardment from the surrounding matter, causing the well known effect of Brownian movement, the paths of particles becoming very ragged and irregular.

35 particles becoming very ragged and irregular. The resultant pattern acquires thereby a very fancy shape, resembling floral designs, like flowers, trees, etc. Upon reaching a certain stage of development, the movement of particles stops, and the printing member is then
40 ready for use. Its design is transferred on a cloth in a simple manner by pressing same directly on the printing member.

45 My invention is described more fully in the accompanying specification and drawings in which—

Fig. 1 is a view of the design commonly obtained by my method with a comparatively thick gelatinous solution, Fig. 2 is a similar design obtained with a thinner solution, Fig. 50 3 is a design obtained with two shades of

color, and Fig. 4 is a design where two or more colors are combined and commingled by the operator.

In order to prepare a printing member a gelatinous solution is prepared by boiling Irish moss with water, thereby providing a color carrying material. The relative amount of moss used and the time of boiling determine the density of the solution which in turn determines the shape of the pattern of the design obtained with my process. Where Irish moss is used the gelatinous solution preferably comprises one pound of Irish moss in five gallons of water. This is boiled down to a jelly and is screened through a cloth to filter out lumps. The solution is then ready for use. The more liquid the solution the greater will be the spread of the dye and the stiffer the solution, the less will be the spread. The consistency of the solution is determined by the time of boiling.

The solution, when ready, is spread in a shallow layer over the surface of a suitable support, for example, glass, metal plate or a similar material. The thickness of this gelatinous layer may vary, but I found that satisfactory results are obtained with the layer about one millimeter thick, or $3/64''$, and forms a support or carrier for the dyes. 75

Other material may be used instead of Irish moss such as various viscous materials, or materials which produce a colloidal gelatinous substance when boiled with water. 80

For preparing patterns I may use water soluble aniline dyes by boiling them in water until a desired shade of color is obtained. Any type of commercial aniline dye or color may be used in carrying out the present invention. This dye or color may be made in the usual way of three ounces of dye to one gallon of water. If a less dense color is desired, then more water is added. 85 90

One method of applying the dye is by placing the solution in ordinary glass droppers with rubber bulbs. By squeezing lightly the bulbs, drops of dye solutions are deposited on the color carrying material. Each drop immediately spreads out in thin streaks of a very irregular and fancy shape as shown in Fig. 1 which illustrates a case when a com- 95
100

paratively thick gelatinous solution is used as a support. The explanation of this phenomenon lies, probably, in the molecular nature of the materials used. The particles of 5 dye, being extremely minute, are subjected to bombardment by molecules of the gelatinous material in a similar manner as it is observed in Brownian movement of minute suspended particles. The dye solution rapidly 10 spreads around on account of the attraction of the gelatinous matter, and the molecular bombardment causes sudden changes in a direction of movement of its particles, producing a zig-zag pattern.

15 The attraction is less with a thick solution in which case a less rapid movement is obtained, the dye does not spread out as far, and the streaks become more ragged and irregular (Fig. 1). Somewhat increased attraction 20 causes different patterns to appear as shown in Fig. 3.

The pattern of the design is more or less fixed for the gelatinous solution of a given consistency, so that it becomes possible to 25 cover the whole surface of the matrix with a uniform design by dropping dye solution in drops at regular intervals of space.

It is also possible to apply layers of gelatinous composition of different consistency in 30 different places on the matrix, merging them gradually, in which case the pattern of the design will vary on different portions of the printing bed. For instance, by starting with a thin solution of the gelatinous matter and 35 gradually increasing the consistency of the solution from one end of the printing bed to the other, an interesting effect is obtained by gradual transition from patterns similar to Fig. 1 to patterns of the Fig. 3.

40 The pattern can be varied by using dyes of different colors or shades. Fig. 3 illustrates a case when a small drop of black dye was placed in the middle of the first drop producing effect of the shaded central portion, the 45 whole picture resembling a flower. This effect was accentuated by drawing a glass rod through the drops, thereby producing the effect of a stem on the flower.

By varying the size of drops the resultant 50 pattern may be accordingly varied, each drop producing an individual pattern with an approximately circular outline, if the dye is unobstructed in its movement. This pattern can be more or less substantially changed, for 55 instance, by crowding successive drops closer together, inserting small drops between the large patterns, alternating colors and shades by using drops of different dyes and of different consistency etc.

60 A different effect is produced when the dye is dropped at an angle, for instance, if the printing bed is more or less inclined.

Another effect is obtained if, after the basic 65 design has been produced, the space between the individual patterns is sprinkled with fine

droplets of the dye of the same or different color. A brush spraying or similar method can be used for this purpose.

The pattern can be considerably modified if the dye in the process of spreading on the 70 printing bed is worked with a suitable implement. In this manner, for instance, the stem-like extension on the pattern has been produced as illustrated in Fig. 3, by using a glass rod. Wooden sticks, combs, brushes, 75 etc., can be also used for modifying or producing the patterns.

All the basic patterns, although, are produced more or less automatically by my 80 method, are of highly artistic and decorative character, and of more or less intricate design which it is difficult to imitate even for skilled artists by ordinary designing methods.

The design produced by my method on a 85 printing bed, which may be used directly for printing cloth such as silk or wool, or on a similar material, can be also, of course, photographed and reproduced by photoengraving or similar method on metal plates for printing by ordinary methods not only 90 on cloth, but, also, on paper and other materials.

When the printing bed with the desired 95 pattern or design is prepared by my process as above explained, the piece of textile material to be printed is carefully placed on the printing bed in such manner as to float on the top surface of the bed. The dyes comprising the pattern soak into the textile material and apparently are drawn into the material by capillary attraction so that the 100 design is completely and thoroughly transferred to the cloth. After this transfer takes place, the cloth is carefully lifted from the printing bed and is treated by solutions to 105 wash out any of the bed material that may be picked up by the cloth and to set the dyes in the cloth in accordance with the well known methods of the art. After the cloth has been thoroughly cleansed, and the dyes 110 have been set, the cloth is then dried and may be pressed with a hot iron if desired.

The design printed by my process shows 115 fully on both sides of the cloth, and is fast and indelible. When proper dyes are used, it will stand an indefinite number of washings.

Important advantages of my process are 120 that it provides methods for producing rapidly and automatically artistic designs of uniform or varying patterns, for transferring same on textile materials and rendering the transferred designs indelible or fast. No artistic skill is required in the use of my process for producing designs, and their patterns can be varied at will within wide limits. Very little time is required for preparing and completing a printing bed by my method.

The designs are obtained of a highly artistic and decorative nature, which are very dif- 125

ficult to duplicate by ordinary methods, even for highly skilled artists.

I also found that the designs can be modified by adding to the dye solutions a few 5 drops of the extract of the ox gall.

The present invention is applicable to the dyeing of any type of textile material, and is particularly applicable to the dyeing of silk. The use of the word "dye" in the specification 10 and the claims is not limited to any particular kind or character of dye other than those well known in the art and the treatment after the cloth has been dyed is in accordance with the present practice of setting, developing 15 or other treatments to bring out the colors and render the colors permanent.

I claim as my invention:

1. The method of dyeing textile fabrics comprising preparing a gelatinous composition 20 by boiling Irish moss in water, spreading a thin layer of said composition upon a supporting surface, placing small isolated amounts of dye solutions upon said composition, the surface tension between said composition and said dye solution being such as to cause the dye to spread out to form a pattern of a predetermined general type and laying 25 a piece of textile material upon the surface of the composition with the pattern thereon to permit the dye pattern to be transferred 30 to said material.

2. The process of dyeing textile materials comprising preparing a gelatinous solution and spreading the same upon a support to 35 form a printing bed, placing isolated drops of aniline dyes upon said printing bed, the surface tension between said dyes and said printing bed material being such as to cause the dye to spread in a pattern of a predetermined type, mechanically changing the outline 40 of said pattern by moving an instrument through said pattern and laying a sheet of textile fabric upon said printing bed and permitting the dye to soak into said fabric to 45 transfer the pattern thereto.

Signed at New York city in the county of New York and State of New York this 11th day of January A. D. 1929.

50 ALEXANDER J. BELOKOPYTOFF.
